CANNED OIL SERVICER

Filed May 24, 1934

UNITED STATES PATENT OFFICE

1,981,177

CANNED OIL SERVICER

Harry R. Johnson, Baltimore, Ohio

Application May 24, 1934, Serial No. 727,349

2 Claims. (Cl. 221—68)

This invention relates to a canned oil servicer, the general object of the invention being to provide a stand having shelves thereon on which the cans of oil are placed and the top shelf of which acts as a support for the cans being opened, so that the cans are not placed on the pavement or other part where the can may become dirty, with danger of the dirt dropping into the oil being placed in the crank case of the car. 10 The device can also be used for advertising the oil and it provides a neat and attractive means for displaying the oil.

Another object of the invention is to provide means whereby the oil draining from the funnel can be caught in a can placed in the lower part 15 of the device.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing where- 20 in like characters denote like or corresponding parts through the several views, and in which:—

Figure 1 is an elevation of the invention, with one of the doors open.

Figure 2 is a section on line 2—2 of Figure 1.

Figure 3 is a section on line 3—3 of Figure 1.

In these views, the numeral 1 indicates a base and the numeral 2 indicates a pair of uprights which support an intermediate shelf 3 and a top shelf 4. The members 1, 3 and 4 are shown as 35 of circular shape and each of these members may be formed with an upstanding flange so as to prevent the cans A of oil and the cans A' from being pushed off the members. A pair of doors 5 is hinged to one of the uprights 2, as shown at 6, 40 these doors being of substantially semi-circular form in cross section and are provided with the latch means 7 for engaging the keepers 8 on the other upright. Oppositely arranged holes are formed in the upper shelf 4 and the enlarged end 45 9 of a tube 10 is suitably held in each hole, these tubes passing through holes in the shelf 3 and each tube having a short tube 11 slidably connected with its lower end, these tubes 11 being adapted to fit in openings in the cans A' placed 50 on the shelf 1 so as to receive oil dripping from

funnels, such as shown at B, when the funnels are placed in the enlarged ends 9 of the tubes 10. The funnel B is of the bladed type for punching holes in the cans A and as will be understood, when a customer drives up to the service station, 55 a can of oil is placed on the shelf 4, the funnel placed over the same in inverted position and pressed upon to cause the knives to punch holes in the top of the can. Then the can, with the funnel thereon, is inverted, with the end of 60 the funnel in the oil receiving tube of the motor of the car. After the can is empty, the small end of the funnel is placed in the enlarged upper end 9 of one of the tubes 10 so that the oil from the funnel will drain through 65 the tube into one of the cans A'. Thus the device will be kept free of oil with the minimum amount of effort and this oil which usually goes to waste is saved. As shown, the doors 5 simply cover that part of the device below the 70 intermediate shelf 3, so that the cans placed on the shelf 3 are visible and act as advertising means and advertising matter can be placed on the outer faces of the doors, if desired. By having the tube 11 slidably arranged on the lower 75 end of each tube 10, this tube can be raised and lowered so that the can A' can be readily removed from under a tube or placed thereunder.

It is thought from the foregoing description that the advantages and novel features of the 80 invention will be readily apparent.

It is to be understood that changes may be made in the construction and in the combination and arrangement of the several parts, provided that such changes fall within the scope of 85 the appended claims.

What is claimed is:—

1. A device of the class described comprising uprights, a base to which the lower ends of the uprights are connected, an intermediate and a top shelf supported by the uprights, said shelves being adapted to support cans of oil with the top shelf receiving the can which is to be opened by a knifed funnel, and a tube leading from the top shelf to a point adjacent the base, the upper end 90 of the tube having a cylindrical enlargement, the upper end of which passes through a portion of the top shelf with its upper extremity flush with the upper surface of the shelf, said upper end 95 receiving the spout of the funnel, after the funnel 100

has been used, and the base receiving a can into which the oil passes from the tube.

2. A device of the class described comprising a base, a pair of oppositely arranged uprights rising from the base, an intermediate and a top shelf supported by the uprights, said shelves being adapted to support cans of oil with the top shelf receiving the can which is to be opened by a knifed funnel, a pair of substantially semi-circular doors for closing the space between the intermediate shelf and the base, each door being hinged at one upright, lock means connecting

each door to the other upright, a tube having an enlarged cylindrical upper end passing through the top shelf with its upper extremity flush with the upper face of the shelf, said tube passing through the intermediate shelf and terminating above the base, a telescoping tubular part on the lower end of the tube, said tube being adapted to receive a funnel in its upper portion and to drain the oil therefrom into a can placed on the base, the intermediate and top shelves being of circular shape. 80 85 90
